APPARATUS FOR HANDLING A CARTRIDGE BELT

Dedrick A. Maanum, Minneapolis, Minn.

Application June 6, 1952, Serial No. 292,082

1 Claim. (Cl. 86—47)

This invention relates to an apparatus and method for handling a cartridge belt, such as a machine gun cartridge belt, and disposing the same in a container from which it may be removed as it is used. In the operation of an automatic firing weapon, such as a machine gun, cartridges are fed into the breech of such a gun by means of a continuous flexible belt adapted to hold said cartridges in a spaced relation. The belt in a loaded condition is a heavy and cumbersome to handle either in carrying the same or feeding the same into a weapon. Therefore it is desirable that such a cartridge belt be packed in a conveniently handled container from which it may be withdrawn as it is used.

It is an object of this invention to provide an apparatus for handling a cartridge belt and disposing the same in a container in a predetermined formation comprising a support for said belt, guide means for holding said belt in layers, means for holding said belt at spaced points, and means for discharging said folded belt downwardly from said support into a container to cause said belt to take a certain formation therein.

It is another object of this invention to provide an apparatus for handling a cartridge belt and disposing the same in a container having in combination, a stand comprising a horizontal member for supporting said belt, said member having an opening intermediate its ends beneath which an open top container may be placed to receive said belt, means carried by said member for guiding the folding of said belt in successively shorter layers; said support comprising members at each end of said opening adapted to be raised upwardly to raise said belt and to drop the same into said container in a certain formation.

It is another object of this invention to provide an apparatus for handling a cartridge belt and disposing the same in a container having in combination, a stand comprising a substantially horizontal support for said belt, said support having an opening intermediate its ends beneath which a container having an open top may be placed to receive said belt, a substantially vertical member disposed at one side of said opening adapted to guide the folding of said belt in successively shorter layers, said support comprising upwardly inclined members disposed at each end of said opening, plate members placed over said upwardly inclined members and respectively extending for some distance beyond the ends of said inclined members, means carried by said plate members for releasably holding the ends of the first layer of said belt whereby said plate members may be lifted upwardly at their outer ends to raise said belt and to drop the same into said container in a certain formation.

It is also an object of this invention to provide a method for handling a cartridge belt and disposing the same in a container which consists in placing said belt upon a member having an opening intermediate its ends beneath which a container having an open top can be placed to receive said belt, folding said belt in successively shorter layers and raising the ends of said belt upwardly for causing said belt to drop through said open-

2

ing and into said container and be folded into a predetermined position.

It is a further object of this invention to provide a method of handling a cartridge belt and disposing the same in a container in a predetermined formation which consists in folding said belt in layers on a support, holding said belt at spaced points and discharging said folded belt into a container to cause the same to take a certain formation therein.

These and other objects and advantages of the invention will be fully set forth in the following description made in connection with the accompanying drawings in which like reference characters refer to similar parts throughout the several views and in which:

Fig. 1 is a view in side elevation showing some parts in section and some parts in dotted lines;

Fig. 2 is a plan view showing some parts in dotted line;

Fig. 3 is a broken view in end elevation showing some parts in dotted line and some parts broken away; and

Fig. 4 is a broken view taken on line 4—4 of Fig. 2 in the direction of the arrows.

Referring to the drawings, a rack for handling cartridge belts comprising a frame 10 is shown. Said frame is generally rectangular in form and while it could be variously made, in the embodiment of the invention as illustrated it is disclosed as being made of wood. Said frame has a back member 10a, leg members 10b, a top member 10c and a bottom member 10d. Said back member is disclosed as being made of suitable boards disposed in vertical relation to member 10c and being secured to the rear side thereof by suitable means, such as wood screws or nails. Said member 10a extends for some distance above member 10c. Members 10c and 10d are shown as being generally rectangular in plan. Leg members 10b are respectively secured by suitable means to members 10c and 10d to their respective corner portions. A member 10e is disposed across the rear of said member 10 being secured to the rear edge portion of member 10d and to the rear leg members 10b and said member 10e extends for some distance upwardly from member 10d. Secured to the front portion of member 10a is a member 11. While said member 11 could be variously made, in the embodiment of the invention illustrated it is made of a board which has portions cut therefrom of right triangular form at each of its ends to form series of steps. Disposed intermediate the ends of member 11c is an opening 13 which is rectangular in plan having a substantial length and a width adapted to accommodate said cartridge belt. Disposed at each end of said opening 13, extending outwardly therefrom and being secured to the top surface of member 10c are upwardly inclined members or wedge-shaped members 14 and 15. Said members are slightly less in width than said opening 13. Respectively overlying members 14 and 15 and resting thereon are plate members 16 and 17. In the embodiment of the invention as illustrated, said plate members are made of sheet metal. Said plate members 16 and 17 are adapted to extend longitudinally over the inner ends of members 14 and 15 and to project for a short distance over said opening 13. Said members 16 and 17 respectively have inner end portions 16c and 17c of a reduced width. Said members 16 and 17 respectively extend outwardly longitudinally from members 14 and 15 for some distance. Members 16 and 17 have spaced openings 16a, 16b and 17a, 17b therein. Said openings are generally rectangular in plan. Adapted to be disposed in said openings 16a and 16b respectively are plate members 18 and 19, and disposed in openings 17a and 17b are plate members 24 and 25. Said members 18 and 19 and 24 and 25 are respectively hingedly secured to bars 20, which bars are secured by

suitable means to the under side portions of members 16 and 17 adjacent the rear end portions of members 14 and 15 respectively. Said bar members 20 are adapted to hold members 16 and 17 from sliding inwardly of members 14 and 15 respectively while members 16 and 17 are resting thereon by engaging the outer ends of members 14 and 15. Said members 18 and 19 and 24 and 25 extend beyond the outer ends of said openings 16a, 16b and 17a and 17b respectively at their under sides. Connecting the rear end portions of members 18 and 19 and secured thereto is a cross member 21. Similarly member 27 is secured to and connects the rear end portions of members 24 and 25. The front end portions of said members 18 and 19 are movable upwardly of said openings 16a and 16b and have hook members 18a and 19a respectively formed at their front end portions each being adapted to partially embrace a cartridge in said belt. Said members 18 and 19 may be made of any suitable material and are herein disclosed as being made of sheet metal. Similarly the front end portions of members 24 and 25 are movable upwardly of openings 17a and 17b respectively and have hook members 24a and 25a formed at their front end portions.

An elongated plate member 28 generally rectangular in form is hingedly secured onto member 10c and is disposed longitudinally thereof adjacent its front edge portion by hinge members 30 and 31. Said member 28 is of slightly shorter length than member 10c, being spaced inwardly from each end thereof, and is adapted to swing outwardly to a horizontal position and may be swung upwardly and inwardly to a vertical position in relation to the surface of member 10c.

A pair of upstanding members 33 and 34 are secured to member 10d and extend upwardly and are spaced apart to be respectively in vertical alignment with the ends of opening 13. Said members 33 and 34 are adapted to hold therebetween a container 36. Said container 36 is generally rectangular in horizontal and vertical section and has an open top. The same may be made of any suitable material, such as metal, fiberboard or wood and is adapted to receive therein a cartridge belt. Said member 36 is positioned so that its open top is in alignment with opening 13.

In carrying out applicant's method, an end portion of a cartridge belt will be placed on member 10c. A cartridge belt generally comprises connected spaced clips adapted to hold a shell or cartridge therein. Said cartridges extend transversely of said belt in said clips and said cartridges and clips form a hinge so that the same with said belt form an articulated flexible structure. The hook members 18a, 19a, 24a and 25a are adapted to be respectively disposed about spaced cartridges. Said hook members 18a and 19a will be placed about the first cartridge in the belt. Hook members 24a and 25a will be placed about the casing of a cartridge some distance from the first cartridge and the remaining portion of the cartridge belt will be folded in layers which will become successively shorter in accordance with the vertical edges in the ends of the steps in member 11. Therefore it is seen that hook members 18a, 19a, 24a and 25a hold the first layer of said folded cartridge belt in position and the large portion of said folded cartridge belt overlies the opening 13. As said cartridge belt is being folded, member 28 will be raised to a vertical position and said cartridge belt will be held in vertical position between said member 28 and member 10a. An open top container 36 is preliminarily placed on member 10d between the members 33 and 34 which positions said container beneath said opening 13 and in alignment with the same. When the cartridge belt has thus been folded, the operator places a hand on each of members

16 and 17 at their outer ends and raises said outer ends, thus raising the outer end portions of said folded cartridge belt. The ends of the first layer of said cartridge belt are held in position by said hook members, as described. The central portion of said folded cartridge belt will thus be lowered into said container. The inner ends of members 16 and 17 are also lowered for some distance into container 36 to guide the loaded belt until the stretches thereof at the ends engage the bottom of container 36. Members 16 and 17 will then be moved upwardly and the belt is discharged into container 36 and takes the predetermined formation shown in Fig. 1. When said folded cartridge belt has been fully received in container 36, the end cartridges of the first layer of said belt, which are still held by the hook members as described, will be in position as the top shells respectively at opposite sides of said container. The operator then moves cross members 21 and 27 upwardly and this will release said hook members from the cartridges held by them. Members 16 and 17 will be withdrawn from said container and said folded cartridge belt will be fully packed therein as shown.

By this arrangement, when the belt is to be used, the operator removes the upper end portion of the belt first and the layers of the belt are easily and successively withdrawn from said container without failing as said cartridge belt is used and fed into the breech of a gun.

Thus it is seen that I have provided a very simple and efficient method and apparatus for handling a cartridge belt and disposing the same in a container. By use of the apparatus and the method herein disclosed, an operator can quickly and easily handle a cartridge belt, folding the same accurately and uniformly and pack the same in desired predetermined formation in a container. The invention has been amply tested in actual practice, found to be very successful and the same is being used commercially.

It will of course be understood that various changes may be made in the form, details, arrangement and proportions of the apparatus and in the steps and sequence of steps of the method without departing from the scope of applicant's invention, which, generally stated, consists in a method and apparatus capable of carrying out the objects above set forth, such as disclosed and defined in the appended claim.

What is claimed is:

An apparatus for handling a cartridge belt and disposing the same in a container having in combination, a stand comprising a substantially horizontal support for said belt, said support having an opening intermediate its ends beneath which a container having an open top may be placed to receive said belt, upwardly inclined members extending oppositely at each end of said opening and being secured to said support, plate members respectively overlying said last mentioned members and extending outwardly at each end therefrom, said plate members respectively having a pair of elongated openings therein, members adapted to be disposed in said openings, hinges securing said last mentioned members respectively to said plate members, said hinges abutting against the outer ends of said upwardly inclined members, and hooks carried by said last mentioned members adapted to releasably hold portions of said belt until said cartridge belt is disposed in said container.
